CLAIM

The ornamental design for a mop cloth, as shown and described.

DESCRIPTION

FIG. 1 is a front elevation view of a mop cloth showing my new design;

FIG. 2 is a back elevation view thereof;

FIG. 3 is an enlarged left side view thereof, which is a mirror image of a right side view; and,

FIG. 4 is an enlarged top plan view thereof, which is a mirror image of a bottom plan view.

The broken lines in the drawing illustrate portions of the mop cloth that form no part of the claimed design. The jagged lines in the drawings show a broken away segment.
